[57] CLAIM

The ornamental design for a wall mounted dryer, as shown and described.

DESCRIPTION

FIG. 1 is a perspective view of the wall mounted dryer, showing my new design;

FIG. 2 is a side elevation view thereof;

FIG. 3 is a bottom plan view thereof;

FIG. 4 is a rear elevation view thereof;

FIG. 5 is a top plan view thereof;

FIG. 6 is a perspective view of a second embodiment of a wall mounted dryer which differs from the first embodiment only in the absence of a visable start button; and

FIG. 7 is a bottom plan view of the second embodiment shown in FIG. 6.

FIG. 1.

FIG. 3.

fig. 2.

fig. 4.

fig. 5.

FIG. 6.

FIG. 7.
